UNITED STATES PATENT OFFICE.

LILLIAN PAGE, OF PACKWAUKEE, WISCONSIN.

SEWING-MACHINE FOOT.

1,211,340.

Specification of Letters Patent. Patented Jan. 2, 1917.

Application filed March 18, 1916. Serial No. 85,116.

To all whom it may concern:

Be it known that I, LILLIAN PAGE, a citizen of the United States, residing at Packwaukee, in the county of Marquette and State of Wisconsin, have invented new and useful Improvements in Sewing-Machine Feet, of which the following is a specification.

This invention relates to a foot adapted to be applied to a sewing machine and it consists in the novel features hereinafter described and claimed.

An object of the invention is to provide an attachment of the character indicated adapted to be applied to the arm or other part of a sewing machine and which serves as means for protecting the fingers of an operator from the action of the needle while sewing.

10 The present invention may be used in lieu of the ordinary pressure foot now generally employed upon a sewing machine and the attachment will perform the same useful functions as the said pressure foot.

15 With the above object in view the improved foot comprises a plate of sheet metal having a slotted end portion adapted to be applied to the bar or standard of the machine by the use of a set or similar screw.

20 The plate is provided with a slotted depressed portion through which the needle of the machine may operate. At the opposite sides of the said slot the plate is provided with upstanding flanges having notches at 25 their upper edges through which the thread may be passed when the needle is being threaded. The said plate is further provided at one end with upstanding tongues adapted to serve as shields and prevent the 30 fingers of the operator from getting under the needle.

In the accompanying drawing, Figure 1 is a perspective view of the foot, showing the same applied to a machine. The other 35 figures are detail views of the structure of the foot.

The foot is formed from a piece of sheet metal having a slotted end 1. The screw or other securing device which is used for attaching the foot to the machine is passed through the slot of the end portion 1 and the improved foot may be used in lieu of the usual pressure foot employed upon a sew-

ing machine. From the slotted end portion 1 the plate is extended down as at 2 approximately at a right angle to the plane in which the surface of the slotted end portion 1 lies. From the lower edge of the extension 2 the plate is extended in the form of a ledge 3 which is slotted at one end as 55 at 4. The material of the plate beyond the opposite edges of the slot 4 is folded over upon the upper surface of the ledge 3 and is then extended vertically forming flanges 5 located at the opposite sides of the slot 4. 60 The said flanges 5 are provided at their upper edges with notches 6 through which the thread may be passed during the operation of threading the needle of the machine. Curved tongues 7 are provided at the slot- 65 70 end of the ledge portion 3 and the said tongues are located at the opposite side edges of the slot 4. When the device is applied to a sewing machine it is secured in position by means of a set screw 8 which passes 75 through the slot of the end portion 1 and secures the said end portion to the lower end of the standard or bar 9 of the sewing machine. The needle indicated at 10 is adapted to operate through the slot 4 of 80 the ledge portion 3 during the operation of sewing.

From the above description taken in conjunction with the accompanying drawing it will be seen that a foot piece of simple and 85 durable structure is provided and that the same when applied to the standard or bar of a sewing machine will perform all of the functions of the usual pressure foot and at the same time the parts and features of the 90 improved foot are so disposed as to effectively protect the fingers of the operator during the sewing operation.

Having described the invention what is 95 claimed is:—

A sewing machine pressure foot comprising a single piece of sheet metal having a slot, and folded upon itself at its side edges and having flanges extending upwardly from said folded portions.

In testimony whereof I affix my signature in presence of two witnesses.

LILLIAN PAGE.
